COACH BODY FOR CAMPING OR THE LIKE

Charles Q. Miner, Rte. 4, Box 233, Boise, Idaho

Filed Oct. 10, 1961, Ser. No. 67,036

Term of patent 14 years

(Cl. D14—3)

Des. 193,388

FIGURE 1 is a rear perspective view of a coach body for camping or the like, showing my new design;

I claim:

The ornamental design for a coach body for camping or the like, substantially as shown.
